UNITED STATES PATENT OFFICE.

ALBERT STUART SPEIRS, OF CHICAGO, ILLINOIS.

SMOKING-PIPE.

SPECIFICATION forming part of Letters Patent No. 707,268, dated August 19, 1902.

Application filed November 26, 1901. Serial No. 83,782. (No model.)

To all whom it may concern:

Be it known that I, ALBERT STUART SPEIRS, a citizen of the United States, residing at Chicago, in the county of Cook and State of Illinois, have invented a new and useful Tobacco-Pipe, of which the following is a specification.

The invention relates to smoking-pipes, and has for its object to provide a device of this class wherein the draft opening or orifice is in the bottom of the tobacco receptacle or bowl, with means whereby the clogging of the orifice may be prevented or accumulations of packed tobacco at the orifice may be readily removed without disturbing the charge, and also to provide improved means for collecting moisture or saliva at a point out of contact with the charge in the bowl, for straining the smoke in its passage to the stem, and for removing accumulations and cleansing the saliva-receptacle.

Further objects and advantages of the invention will appear in the following description, and the novel features thereof will be particularly pointed out in the appended claims, it being understood that changes in the form, proportion, and minor details of construction may be resorted to without departing from the spirit or sacrificing any of the advantages of this invention.

In the drawings, Figure 1 is a side view of a pipe constructed in accordance with my invention, the strainer and wiper being indicated in dotted lines. Fig. 2 is a longitudinal sectional view of the same. Fig. 3 is a detail view of the strainer and wiper detached.

Similar reference characters indicate corresponding parts in all the figures of the drawings.

The bowl 1 may be of any ordinary shape or contour, bored or otherwise hollowed out to form an upper tobacco-receptacle 2 and a subjacent saliva-receptacle 3, which is open at its lower end and is preferably of even diameter throughout, said receptacles being connected at the center of the bottom of the tobacco-receptacle by a draft or smoke orifice 4, preferably of small diameter and particularly of less diameter than the saliva-receptacle. The stem-opening 5 is formed in the side of the saliva-receptacle above its lower end, and the bottom of the saliva-receptacle is normally closed by a removable filling-plug 6.

The advantage of the above-described construction resides in the fact, first, that the smoke-orifice being in the center of the bottom of the tobacco-receptacle insures a central draft through the contents of the pipe, and hence an even burning of the tobacco, second, that the side or the stem-opening is protected from, and therefore cannot be choked or clogged by, the tobacco, and, third, that moisture and saliva passing down the stem is accumulated in the saliva-receptacle below the plane of the stem-opening and out of the path of the smoke, and hence does not affect the quality of the smoke or interfere with the draft.

The cleaning-plug by which the saliva-receptacle is closed preferably projects beyond the bottom of said receptacle to form a knob or grip by which it may be grasped to facilitate removal and, preferably, as shown in the drawings, the bottom of the bowl is concaved or the bottom of the saliva-receptacle is inset to form a cavity 7 in which this knob or grip is located, so that the latter is arranged wholly within the contour of the bowl and above its lower extremity or edge, which, preferably being flat, forms a suitable rest by which the pipe when not in use may be placed in an upright position upon a flat support.

Movably mounted in the smoke-orifice is a wiper or stirrer 8, preferably capable of swinging or turning to traverse that portion of the bottom of the tobacco-receptacle which is adjacent to the orifice, and in practice it is preferred to provide this wiper with a stem 9, extending downward through the orifice (so that its movement in the orifice may prevent the choking thereof) and attached to the filling or cleaning plug, whereby the turning of the wiper may be effected by turning the plug and whereby the axial or upward-and-downward movement of the stem and wiper-arm may be effected by a corresponding manipulation of the plug. The wiper-arm preferably extends laterally beyond the side of the smoke-orifice and may be of a sufficient yielding quality to allow it to bend or straighten in withdrawing the plug from the bottom of the bowl. Obviously, the withdrawal of the wiper from the bowl will cause the effective cleaning of the smoke-orifice the upward-and-downward movement of the plug will

cause the loosening of the tobacco adjacent to and in the orifice, and the turning movement of the plug will effect the removal of packed accumulations of tobacco adjacent to 5 the orifice. Moreover, the saliva-receptacle in the path of the smoke in passing from the orifice to the stem may be provided with an absorbent or straining packing or filling 10, of which the construction may be varied. 10 Preferably, however, this straining or filtering material is carried by the stem of the wiper and may consist of absorbent cotton (medicated, if desired) or bristles, which may be readily cleansed of accumulations when the 15 plug has been removed from the bowl. In practice this straining or filtering material may extend upward on the stem sufficiently to lie adjacent to or in the smoke-orifice, so that smoke in its passage to the stem passes 20 directly therethrough.

Having described the invention, what is claimed is—

1. A tobacco-pipe having a tobacco-receptacle and a smoke-orifice, and a movable 25 wiper having its stem mounted in said orifice and having an arm arranged within the tobacco-receptacle to traverse the surface of its wall.

2. A tobacco-pipe having a tobacco-receptacle and a smoke-orifice, and a rotary wiper 30 having its stem mounted in said orifice and having an arm arranged within the tobacco-receptacle to traverse its wall.

3. A tobacco-pipe having its bowl provided 35 with a tobacco-receptacle and a smoke-orifice in the bottom thereof, and a rotary wiper having its stem mounted in said orifice and having an arm extending laterally therefrom to traverse the surface of the bottom of the 40 receptacle adjacent to said orifice.

4. A tobacco-pipe having its bowl provided with a tobacco-receptacle and a smoke-orifice in the bottom thereof, a saliva-receptacle in communication with the smoke-orifice, and a 45 stem-opening in the wall of the saliva-receptacle, and a wiper having its stem extending through said saliva-receptacle and smoke-orifice provided with a lateral wiper-arm arranged within the tobacco-receptacle for traversing the bottom of the latter adjacent to the 50 smoke-orifice and provided with a handle located exteriorly of the bowl.

5. A tobacco-pipe having its bowl provided 55 with tobacco and saliva receptacles connected by a smoke-orifice and having a stem-opening communicating with the saliva-receptacle at its side, a filling-plug closing the lower end of the saliva-receptacle, and a wiper carried by said plug extending through said smoke-orifice and having an arm for traversing the inner surface of the bottom of the smoke-receptacle.

6. A tobacco-pipe having its bowl provided 65 with tobacco and saliva receptacles connected by a smoke-orifice and having a stem-opening communicating with the saliva-receptacle at its side, and a movable filling-plug fitted in

the bottom of the saliva-receptacle, and a wiper having its stem attached to said plug and extending through the smoke-orifice into 70 the tobacco-receptacle and having an arm for traversing the inner surface of the tobacco-receptacle.

7. A tobacco-pipe having its bowl provided 75 with tobacco and saliva receptacles connected by a smoke-orifice and having a stem-opening in the side of the saliva-receptacle, a cleaning-plug removably fitted in the lower end of the saliva-receptacle, a wiper carried by the plug and extending through the smoke-orifice 80 into the tobacco-receptacle, and a strainer or filter arranged in the saliva-receptacle between the smoke-orifice and the stem-opening.

8. A tobacco-pipe having its bowl provided 85 with tobacco and saliva receptacles connected by a smoke-orifice and having a stem-opening in the side of the saliva-receptacle, a cleaning-plug removably and revolvably fitted in the bottom of the saliva-receptacle, a wiper 90 carried by the plug and having its stem extended through the smoke-orifice into the tobacco-receptacle and provided with a wiper-arm arranged within the tobacco-receptacle to traverse the wall thereof, and a strainer 95 or filter carried by the stem of the wiper.

9. A tobacco-pipe having its bowl provided with tobacco and saliva receptacles connected by a smoke-orifice and having a stem-opening in the side of the saliva-receptacle, a plug 100 fitted in the lower end of the saliva-receptacle, a wiper having its stem attached to the plug and extending through the smoke-orifice into the tobacco-receptacle and carrying a wiper-arm, and a straining or filtering medium carried by said stem and projecting into the 105 smoke-orifice.

10. A tobacco-pipe having its bowl provided with a tobacco-receptacle, a saliva-receptacle arranged below the tobacco-receptacle and in 110 communication therewith by a smoke-orifice, and a cavity below the saliva-receptacle and communicating therewith by an opening through which the contents of the saliva-receptacle may be removed, the saliva-receptacle having a stem-opening in its wall, a plug 115 removably fitted in the opening in the bottom of the saliva-receptacle, and having a handle or grip projecting beyond the bottom of the saliva-receptacle and arranged wholly 120 in said cavity below the saliva-receptacle, and a wiper carried by the plug and extending through the smoke-orifice into the tobacco-receptacle to clean the same.

11. A tobacco-pipe having its bowl provided 125 with tobacco and saliva receptacles and a communicating smoke-orifice, and having a stem-opening in communication with the saliva-receptacle, and a wiper having its stem extending from the saliva-receptacle through 130 the smoke-orifice and provided at its inner end with a flexible wiper-arm arranged within the tobacco-receptacle and insertible and removable through the smoke-orifice.

12. A tobacco-pipe having tobacco and saliva receptacles connected by a smoke-orifice and provided with a stem-opening in communication with the saliva-receptacle, and a 5 wiper having a stem extending from the saliva-receptacle through the smoke-orifice, provided at its inner end with a lateral flexible wiper-arm arranged within the tobacco-receptacle, and having its stem provided with 10 a straining or filtering medium arranged within the saliva-receptacle.

13. A tobacco-pipe having tobacco and saliva receptacles connected by a smoke-orifice and provided with a stem-opening in communication with the saliva-receptacle, and a 15

wiper having a stem extending from the saliva-receptacle through the smoke-orifice, provided at its inner end with a lateral flexible wiper-arm arranged within the tobacco-receptacle, and having its stem provided with 20 a straining or filtering medium arranged within the saliva-receptacle and projecting into the smoke-orifice.

In testimony that I claim the foregoing as my own I have hereto affixed my signature in 25 the presence of two witnesses.

ALBERT STUART SPEIRS.
